UNITED STATES PATENT OFFICE.

PERRY BROWN, OF CORAOPOLIS, PENNSYLVANIA.

BRAKE.

1,185,976.

Specification of Letters Patent. Patented June 6, 1916.

Application filed February 26, 1915. Serial No. 10,784.

To all whom it may concern:

Be it known that I, PERRY BROWN, a citizen of the United States, and a resident of Coraopolis, in the county of Allegheny and 5 State of Pennsylvania, have invented certain new and useful Improvements in Brakes, of which the following is a specification.

This invention relates to improvements in 10 ratchet brakes particularly of that type in which the operating handle is arranged to drop by gravity to an inactive position. In the preferred embodiment of my present invention, when the operating handle is lifted 15 from the vertical to the horizontal position, a ratchet wheel is rotated so as to simultaneously move a gear wheel, the gear wheel meshing with a vertically moving rack bar to which the brake chain is connected.

20 The invention therefore consists in a brake of this general construction and as hereinafter described and then definitely claimed.

In the drawings accompanying and forming part hereof and which, it will be understood, represent the preferably embodiment of my invention, Figure 1 is an elevation of my brake, with parts shown in section line of section being taken through dotted line 25 1—1 of Fig. 2. Fig. 2 is a vertical section through the line 2—2 of Fig. 1. Fig. 3 is a horizontal section through the line 3—3 of Fig. 1. Fig. 4 is a perspective view of two 30 of the parts detached. Fig. 5 is a sectional 35 detail of the ratchet; the gear and the upper part of the rack.

Referring now to the details of the drawings by numerals: 7 designates a casing having a bracket 8 projecting from its upper 40 end as shown in Fig. 2, this bracket having two ribs 9 and 10 forming a channel between them. Within this channel is designed to fit the upper rail 11 of an open ended car. Rivets 12 and 13 are employed 45 to secure the bracket 8 to the rail 11 as indicated in Figs. 1 and 2. This forms a substantial way of connecting the framework of the brake in position.

The casing 7 is provided with a horizontal 50 cylindrical member 14 which forms a housing for the operative parts of the brake. The rear end of this housing is closed by a

plate 15, a bolt 16 being employed which passes through the vertical part of the casing 7 and through the plate 15 as clearly 55 seen in Fig. 2. It will be evident that instead of securing the casing 7 to a rail as 11, the plate 15 may be backed up against the end wall of a car and the bolt 16 made long 60 enough to pass through the wall of the car 65 and thereby secure the plate 15 and the casing 7 to the end of the car.

Within the casing 7 and inclosed by the cylindrical wall 14 I support on the bolt 16 a ratchet wheel 18 and a gear wheel 19 65 which, in their preferred embodiment, are cast integrally as illustrated in Fig. 2. The ratchet wheel 18 is formed with a hub 20 cast integrally with the end thereof (see Fig. 2) and upon this hub is supported a link 22. This link 22 is provided with a pin or journal 23 which passes into an opening 24 in the upper end of an operating handle or lever 25. This handle or lever 25 projects through an opening 28 in the periphery of the cylindrical part 14 of the casing and the upper end of the handle is provided with a pawl 29 which is adapted to co-act with the teeth of the ratchet wheel 18. This operating handle or lever 25 and the link 22 are substantially like those illustrated and claimed in my application Ser. No. 878,905, filed December 24, 1914. One point of difference is that the link 22 is provided with a lateral lug 30 which projects 80 into the path of a lug 31 formed on the upper end of the operating handle or lever 25 so that when the operating handle or lever is allowed to drop from the horizontal 85 to the vertical position, the lug 30 will contact with the lug 31 as seen in Fig. 1 and thus prevent the pawl 29 from moving too far away from the teeth of the ratchet wheel. The long extended member 33 is designed to close the opening 28 in the periphery of the 90 member 14 and thus prevent snow, ice or water from entering the casing.

The opposite side of the casing is provided with another peripheral opening 35 (see Fig. 1) through which projects a gravity operating dog 36 pivoted upon a pin 37. From an inspection of Fig. 1 it will be seen 100 whenever the operating handle or lever 25 is elevated, the initial movement thereof

- causes the pawl 29 to engage the ratchet wheel 18 and the continued upward movement of the operating handle or lever 25 will thus cause the ratchet wheel to rotate. 5 During this rotation the gravity operating dog 36 moves on its pivot 37 to permit the ratchet wheel to turn, but the dog engages each tooth and holds the same when the operating handle or lever 25 is allowed to drop. 10 One side of the casing 7 is provided with a housing 40 adapted to contain a vertically operating rack bar 41. This casing may be short as indicated in Fig. 1 and have a pipe 42 screwed on its lower end, as illustrated, 15 to form a long extended housing for the rack bar and brake chain. This rack bar is formed with rack teeth 43 on its inner side and these rack teeth are constructed and arranged to engage with the teeth of the 20 gear 19 so that as said gear is rotated in one direction the rack bar 41 will be forced to move upwardly drawing upon the brake chain 44 secured to the lower end of the rack bar 41. The upper end of the rack bar 25 may be held against the gear wheel 19 by means of an anti-friction roller. In Fig. 1 I have illustrated two of these anti-friction rollers 46 and 47 which are located within the side of the housing 40 and bear against 30 the outer side of the rack bar 41 and thus hold the teeth 43 in proper mesh with the teeth of the gear wheel 19 as above stated. In order to more firmly secure the brake in position, the plate 15 of the cylindrical member 14 of the casing 7 is provided with an extension 50 (see Figs. 1 and 3) having a clamping member 51 formed at right angles to the extension 50 and arranged to be clamped around the usual upright standard 40 53; this standard being connected by a guard chain 54 with a similar standard (not shown). From this construction it will be seen that I not only have a casing which is provided with a bracket, as 8, to receive the 45 horizontal rail on the end of a car, but I also employ the extension 50 and its clamp 51 so that the brake casing is effectually secured in position and cannot be twisted out of place by the operation of the brake 50 handle. While the operation of my device will be obvious to those familiar with this class of brakes, it may not be amiss to state that when the brakeman desires to apply the 55 brakes, he grasps the handle or lever 25 and moves it up and down very much in the way that an old fashioned pump would be operated. On the upward movement of the handle the pawl 29 immediately engages one 60 of the ratchet teeth on the wheel 18 and the handle thus swinging upon the link 22 which is journaled upon the bolt 16 causes the ratchet wheel to rotate. Inasmuch as the ratchet wheel and the gear wheel 19 are 65 formed integrally, the gear wheel is caused to rotate simultaneously with the ratchet wheel and the rotation of the gear wheel causes the rack bar 41 to be elevated, thus drawing upon the brake chain 44 and applying the brake. If one upward movement of 70 the handle or lever 25 is insufficient to apply the brake, the handle or lever is allowed to drop by gravity to the position shown in Fig. 1 when the operation may be repeated until the brake is sufficiently applied. During 75 the rotation of the ratchet wheel, the dog 36 slips back as each tooth passes by it, and the ratchet wheel is thereby held against counter-rotation. However, when it is necessary to release the brake, all that the 80 brakeman has to do is to move the dog 36 to the left, as viewed in Fig. 1, when the ratchet wheel will be released and the rack bar allowed to drop to its normal position, thus releasing the brake. 85 It is obvious that changes and modifications may be made in the form and construction of my invention without departing from the spirit thereof, and reference should therefore be made to the appended claims to 90 determine the scope of the invention. What I claim as my invention is: 1. In a brake, a longitudinally movable rack bar, a brake member operated from said rack bar, and an operating handle or lever 95 arranged to drop by gravity to an inactive position, in combination with mechanism interposed between said handle or lever and said rack bar constructed and arranged to move said rack when said operating handle 100 or lever is moved. 2. In a brake, a longitudinally movable rack bar, a brake member operated from said rack bar, an operating handle or lever arranged to drop by gravity to an inactive 105 position, mechanism comprising a ratchet wheel between said rack bar and said handle or lever, and a dog co-acting with said ratchet wheel to prevent counter-rotation. 3. In a brake, a longitudinally movable 110 rack bar, a brake chain connected therewith, a gear for operating said rack bar, and a handle or lever for operating said gear, said handle or lever being arranged to drop by gravity to an inactive position. 4. In a brake, a longitudinally movable rack bar, a brake chain connected therewith, a gear for operating said rack bar, a ratchet wheel movable with said gear, and a handle or lever co-acting with said ratchet wheel to 115 rotate the same and said gear, said handle or lever being arranged to drop by gravity to an inactive position. 5. In a brake, a longitudinally movable rack bar, a brake chain connected therewith, 120 a gear for operating said rack bar, a ratchet wheel movable with said gear, a handle or lever co-acting with said ratchet wheel to rotate the same and said gear, said handle or lever being arranged to drop by gravity to 125 130

- an inactive position, and a dog co-acting with said ratchet wheel to prevent counter-rotation.
6. In a brake, a longitudinally movable rack bar, a brake member operated from said rack bar, a gear for operating said rack bar, a roller co-operating with said rack bar to hold the same in mesh with said gear, a ratchet wheel movable with said gear, and 10 a handle or lever constructed and arranged to rotate said ratchet wheel and gear to give longitudinal movement to said rack bar, said handle or lever being arranged to drop by gravity to an inactive position.
15. In a brake, a longitudinally movable rack bar, a brake member operated from said rack bar, a gear for operating said rack bar, a roller co-operating with said rack bar to hold the same in mesh with said gear, 20 a ratchet wheel movable with said gear, a handle or lever constructed and arranged to rotate said ratchet wheel and gear to give longitudinal movement to said rack bar, and a dog co-acting with said ratchet 25 wheel to prevent counter-rotation, said handle or lever being arranged to drop by gravity to an inactive position.
3. In a brake, a casing, a ratchet wheel therein, a housing connected with said casing, a rack bar entering said housing, a 30 brake member operated from said rack bar, a gear in said casing movable with said ratchet wheel and co-acting with said rack bar, and a handle constructed and arranged 35 to drop by gravity to an inactive position and to rotate said ratchet wheel and thereby operate the gear to move the rack bar when said handle or lever is elevated.
9. In a brake, a casing, a ratchet wheel 40 therein, a housing connected with said casing, a rack bar entering said housing, a brake member operated from said rack bar, a gear in said casing movable with said ratchet wheel and co-acting with said rack 45 bar, a handle constructed and arranged to drop by gravity to an inactive position and to rotate said ratchet wheel and thereby operate the gear to move the rack bar when 50 said handle or lever is elevated, and a dog entering said casing and co-acting with said ratchet wheel to prevent counter-rotation.
19. In a brake, a casing having a bracket 55 adapted to fit onto a platform rail of a car, a ratchet wheel supported in said casing, a brake member operated from said ratchet wheel, and a handle or lever supported by said casing and co-acting with said ratchet wheel to rotate the same when the handle is elevated, said handle or lever being constructed and arranged to drop by gravity to an inactive position.
11. In a brake, a casing having a bracket 65 provided with ribs forming a channel to receive the platform rail of a car, a ratchet wheel supported in said casing, a brake 70 member operated from said ratchet wheel, and a handle or lever supported by said casing and co-acting with said ratchet wheel to rotate the same when the handle is elevated, said handle or lever being constructed and arranged to drop by gravity to an inactive position.
12. In a brake, a casing having a bracket 75 adapted to fit onto the platform rail of a car, a ratchet wheel and a gear wheel supported in said casing, a brake member operated from said ratchet wheel, a handle or lever co-acting with said ratchet wheel to rotate the same and said gear when the handle is elevated, a housing projecting 80 from said casing, and a rack bar moving in said housing and having its teeth meshing with said gear wheel.
13. In a brake, a longitudinally movable bar, a ratchet wheel operatively connected 85 with said bar, a brake member operated from said rack bar, and a handle or lever operating said ratchet wheel, constructed and arranged to drop by gravity to an inactive position.
14. In a brake, a longitudinally movable bar, a ratchet wheel operatively connected with said bar, a brake member operated from said rack bar, a link journaled in proximity to said ratchet wheel, and an operating handle or lever movable with said link and co-acting with said ratchet wheel and constructed and arranged to drop by gravity to an inactive position and to rotate the same as the handle is moved upwardly on 90 said link.
15. In a brake, a longitudinally movable rack bar, a gear wheel meshing with the teeth of said rack bar, a brake member operated from said rack bar, a ratchet wheel 105 movable with said gear wheel, a link journaled in proximity to said ratchet wheel, and an operating handle or lever movable with said link and co-acting with said ratchet wheel and constructed and arranged to drop by gravity to an inactive position and to rotate the same as the handle is moved upwardly on said link.
16. In a brake, a casing having a horizontal axle pin therein, a longitudinally 115 movable bar, a brake member operated from said rack bar, a ratchet wheel supported on said axle pin within the casing and operatively connected with said bar, and a handle or lever for operating said ratchet wheel 120 and arranged to drop by gravity to an inactive position.
17. In a brake, a casing having a horizontal axle pin therein, a longitudinally 125 movable bar, a brake member operated from said rack bar, a ratchet wheel supported on said axle pin within the casing and operatively connected with said bar, a link journaled in proximity to said ratchet wheel, and an operating handle or lever movable 130

- with said link and co-acting with said ratchet wheel and constructed and arranged to drop by gravity to an inactive position and to rotate the same as the handle is moved upwardly on said link. 5
18. In a brake, a casing having a horizontal axle pin therein, a longitudinally movable rack bar, a brake member operated from said rack bar, a gear wheel and 10 ratchet wheel supported on said axle pin within the casing, said gear meshing with the teeth of said rack bar, and a handle or lever for operating said ratchet wheel and arranged to drop by gravity to an inactive position. 15
19. In a brake, a casing having a horizontal axle pin therein, a longitudinally movable rack bar, a brake member operated from said rack bar, a gear wheel and 20 ratchet wheel supported on said axle pin within the casing, said gear meshing with the teeth of said rack bar, a link journaled in proximity to said ratchet wheel, and an operating handle or lever movable 25 with said link and co-acting with said ratchet wheel and constructed and arranged to drop by gravity to an inactive position and to rotate the same as the handle is moved upwardly on said link. 30
20. In a brake, a casing having a horizontal axle pin therein, a housing at one side of said casing, a longitudinally movable bar in said housing, a brake member operated from said rack bar, a ratchet wheel 35 supported on said axle pin within the casing and operatively connected with said bar, and a handle or lever for operating said ratchet wheel and arranged to drop by gravity to an inactive position. 40
21. In a brake, a casing having a horizontal axle pin therein, a housing at one side of said casing, a longitudinally movable rack bar in said housing, a brake member operated from said rack bar, a gear wheel 45 and ratchet wheel supported on said axle pin within the casing, said gear wheel meshing with the teeth on said rack bar, and a handle or lever for operating said ratchet wheel and arranged to drop by gravity to an inactive position. 50
22. In a brake, a casing having a horizontal axle pin therein, a housing at one side of said casing, a longitudinally movable rack bar in said housing, a brake member operated from said rack bar, a gear wheel 55 and ratchet wheel supported on said axle pin within the casing, said gear wheel meshing with the teeth on said rack bar, a link journaled in proximity to said ratchet wheel, and an operating handle or lever movable 60 with said link and co-acting with said ratchet wheel and constructed and arranged to drop by gravity to an inactive position and to rotate the same as the handle is moved upwardly on said link. 65
23. In a brake, a casing having a substantially flat open back adapted to be secured against an end wall of a car, and having a bracket projecting therefrom provided with a channel adapted to receive the end 70 rail of a car, a plate closing the open back of said casing and having an extension provided with a clamp adapted to be secured to a vertical post of a car, an axle pin projecting through said casing, a ratchet wheel 75 on said axle pin within the casing, and an operating handle or lever having a pawl projecting within the casing and arranged to drop by gravity to an inactive position to release said ratchet wheel and to rotate 80 the ratchet wheel as the handle is moved upwardly. 85

In testimony whereof I affix my signature in presence of two witnesses.

PERRY BROWN.
